Charles W. Dann, East Orange, N. J., assignor to
Thomas A. Edison, Incorporated, West Orange,
N. J., a corporation of New Jersey

Application September 24, 1942, Serial No. 108,829

Term of patent 14 years

To all whom it may concern:

Be it known that I, Charles W. Dann, a citizen of the United States and a resident of the city of East Orange, in the county of Essex and State of New Jersey, have invented a new, original, and ornamental Design for a Combined Speaker-Microphone and Control Unit, of which the following is a specification, reference being had to the accompanying drawing, forming a part thereof.

In the drawing:

Figure 1 is a side elevational view of a combined speaker-microphone and control unit according to my design; and

Figures 2 and 3 are respectively front and back elevational views of this combined speaker-microphone and control unit.

I claim:

The ornamental design for a combined speaker-microphone and control unit, substantially as shown.

CHARLES W. DANN.
